ABSTRACT

A photoconductive device is positioned adjacent to a light source with a radiation barrier between them. The radiation barrier has slots, and is rotated, causing light to alternately impinge upon the photoconductive device and to be blocked resulting in alternating decreases and increases in the impedance of the device. By using slots of random width and random spacing, the impedance variation introduced into a circuit simulates noise.

VARIABLE IMPEDANCE GENERATOR

BACKGROUND OF THE INVENTION

This invention relates generally to a variable impedance generator, and more particularly, to a system for simulating the noise normally found in electrical circuits.

As systems such as aircraft, power generating plants, and the like, become larger and more complex, it becomes uneconomical to train operators through experience on the actual system. Simulators which appear to the operator to be the actual operating system are being employed for these training purposes not only because of the economies in so doing, but also because they permit training in emergency procedures which might be hazardous with a real system.

In producing a nuclear power plant simulator it was noticed that the analog indicating devices, i.e., meters, did not accurately simulate those in the real power plant because the indicator needles failed to tremor or kick in the manner of the real meters. The meter needle movement is the result of noise in the system which is normally random both as to frequency of pulses as well as amplitude and disappears when the analog becomes zero. No economical method for simulating this noise was known.

SUMMARY OF THE INVENTION

It is an object of this invention to provide a reliable and economical source of varying impedance.

It is a further object of this invention to provide such a source where the impedance will vary in a pseudorandom manner.

In a preferred form of the invention, a plurality of photoconductive devices (photocells) are positioned so that radiation from a light source will impinge upon them. A disc rotated at a slow speed, and having slots of random width and random spacing is interposed between the light source and the photocells so that the photocells will be exposed to radiation for varying periods of time. Each photocell is connected to a circuit in parallel with a fixed resistance sized to achieve desired overall impedances when the photocells are illuminated and not illuminated. The varying impedance introduced into the circuit simulates noise.

BRIEF DESCRIPTION OF THE DRAWINGS

FIG. 1 is a schematic circuit diagram illustrating one application of the invention; and

FIG. 2 is a schematic isometric of one embodiment of the invention.

DESCRIPTION OF THE PREFERRED EMBODIMENT

Referring to FIG. 1, a plurality of analog indicating devices 10A-10C, each having an internal resistance (in the actual indicators this was 5,000 ohms) represented by resistors 12A-12C respectively is represented. Analog signals derived from sources 14A-14C are provided to their respective indicators. The nature of the analog signals delivered by sources 14A-14C is such that, without additional circuitry, the indicator needle would move to the position designating the analog value without exhibiting noise in terms of the tremor or kick from the analog value normally found in many operating systems. In the case of the system actually built, this lack of noise was due to the fact that the analog signal was artificially generated rather than originating in a transducer, sensor, or the like.

To better simulate the indicator movements found in an actual system, noise had to be added to the analog signals derived from sources 14A-14C with the following limitations:

1. When the analog signal was zero, no movement of the indicator pointer should occur.
2. The noise should appear to be random, and differ in pattern from indicator to indicator.
3. The magnitude of the noise should be such that it would cause changes of as little as 1 percent or as much as 3 percent in the impedance of the analog indicators.

In accordance with the invention, the noise generator illustrated in FIG. 2 was employed. Slotted disc 16 constituting a radiation barrier having radiation transmitting portions is mounted in enclosure 18 so that radiation from light source 20 will impinge upon it. Slotted disc 16 is mounted to be rotated at a slow speed (3 revolutions per minute in the embodiment built), by motor 22. Motor 22 is mounted on the rear of plate 24.

Slots 26 are arranged near the periphery of disc 16 in a random manner both as to width of the slots and spacing between them. Mounted on the forward face of plate 24 are a plurality of photocells 28A-28C. In the fabricated embodiment, 16 Ratheon CK1241 cadmium selenide photocells were mounted in a circular arrangement with the same center and radius as slots 26. Photocells 28A-28C have a resistance of 150 ohms when illuminated by 100 foot candles and a resistance of 20,000 ohms or greater when not illuminated.

With the disclosed arrangement, therefore, as disc 16 rotates, photocells 28A-28C become illuminated for random periods of time at random intervals causing resistance changes between the illuminated and not illuminated values. To decrease the impingement of reflected radiation upon the photocells the reverse surface of disc 16 and the forward surface of plate 24 should be painted flat black. Ambient light is also minimized by making the section of enclosure 18 surrounding slotted disc 16 and plate 24 of an opaque material having a flat black interior surface coating. That part of enclosure 18 covering light source 20 is a perforated screen to protect against breakage and allow ventilation. Maintenance is reduced by operating light source 20 below its rated voltage.

It should be understood that light source 20 can be a source of visible, infrared, or ultraviolet light depending upon the photoconductive material employed in photocells 28A-28C.

Referring again to FIG. 1, photocells 28A-28C are connected in parallel to resistors 30A-30C. By selecting resistors 30A-30C having suitable resistances the desired percentage variation of the impedance can be obtained. For example, if about a 3 percent impedance variation were desired in the indicator reading of indicator 10C, resistor 30C would be chosen to be about 250 ohms. When photocell 28C is illuminated (having 150 ohms resistance) the total impedance is:

$$\frac{250 \times 150}{400} + 5000 = 5094 \text{ ohms}$$

When not illuminated:

$$\frac{250 \times 20000}{20250} + 5000 = 5247 \text{ ohms}$$

The percent change between the illuminated and not illuminated states is:

$$\frac{153 \times 100}{5247} = 2.92\%$$

Since the noise is not added to the analog signal produced, but instead varies the impedance the signal experiences, when the signal goes to zero the indicator will not show noise. Also, by not wiring adjacent photocells to adjacent indicator circuits, but instead using a random arrangement the noise exhibited by adjacent indicators is out of phase and appears random.

While for this particular use a random impedance variation was sought, it can be seen that other slot arrangements on disc 16, for example a regular pattern of equally wide slots, could be used to introduce desired impedance variations into circuits.

Moreover, the basic invention can be applied for other purposes. If, for example, a pair of discs having slots initially aligned are mounted on a shaft, a relative displacement occurs when torque is applied causing a detectable impedance change. In a similar manner slotted discs mounted on independent coaxial shafts can be used to monitor synchronism or phase displacement.

75 I claim:

1. In a system having an analog indicating device for displaying the magnitude of a signal produced by a source, means for varying the impedance experienced by said signal in a pseudorandom manner comprising:

a fixed resistance connected between said source and said indicating device;
a source of radiation;
a photoconductive device positioned to have radiation from said source impinge upon it, and connected in parallel to said fixed resistance;
a disc positioned between said source of radiation and said photoconductive device having a plurality of slots of random width and random spacing arranged about its periphery for transmitting radiation to said device; and
means for rotating said disc so that radiation alternately impinges upon said photoconductive device and is blocked in a pseudorandom manner.

2. In a system having a plurality of analog indicating devices each displaying the magnitude of a signal produced by a source connected to it, means for varying the impedance ex-

perienced by each of said signals in a manner simulating noise comprising:

a fixed resistance connected between each of said indicating devices and its respective source;
a source of radiation;
a photoconductive device connected in parallel with each of said fixed resistances;
said photoconductive devices positioned in a circular pattern to have radiation from said source impinge upon them;
a disc positioned between said source of radiation and said photoconductive devices having a plurality of slots arranged around its periphery having the same radius and center as said photoconductive devices;
said slots being of random width and random spacing; and
means for rotating said disc so that radiation alternately impinges upon said photoconductive devices and is blocked in a pseudorandom manner.
